UNITED STATES PATENT OFFICE.

EUGENE GASE AND LOUIS CHARLES REESE, OF SAGINAW, MICHIGAN, ASSIGNORS TO BAKER-PERKINS COMPANY, INC., OF WHITE PLAINS, NEW YORK.

BRUSH SIFTER.

Application filed February 8, 1923. Serial No. 617,878.

To all whom it may concern:

Be it known that we, EUGENE GASE and LOUIS CHARLES REESE, both residing in the city of Saginaw, county of Saginaw, and State of Michigan, have invented new and useful Improvements in Brush Sifters, of which the following is a specification.

This invention relates to improvements in sifters, and more particularly to a sifting device in which suitable brushes are disposed within a sifting reel in proximity to a screen, which constitutes the sifting means in the device, the brushes serving to keep the screen clean and to assist in the sifting operation.

The primary object of the invention is to provide means in a sifting device whereby the sifting operation may be performed more efficiently than has heretofore been accomplished.

Another object of the invention is to provide means in a sifting device for removing impurities and foreign matter in such a manner as to be more completely removed therefrom than has been accomplished by devices heretofore employed.

A further object of the invention is to provide a machine in which the various parts may be readily and easily adjusted in accordance with the different or various materials to be treated and in which means are provided for counteracting or allowing for the condition of the brushes and screen, thereby attaining more uniform results and minimizing the wear and tear on the apparatus, whereby a saving in power, labor and cost of repairs is effected.

The invention comprises a rotary sifting reel of circular cross section which is preferably in the shape of a truncated cone and is adapted to revolve on a horizontal axis. The smaller end of the truncated cone serves as an inlet for material to be sifted and its larger end as an outlet for the waste material or impurities which do not pass through the screen. Within the reel, stationary narrow brushes are provided which preferably extend the whole length of the reel, whereby the material may be continuously removed from the screen during its rotation. The brushes are preferably made adjustable in position, and means are provided whereby the bristles of the brushes may be maintained uniformly in contact with the inner

surface of the screen. By the means which are provided the action of the brushes is more gentle than in any other sifters heretofore employed, for the reason that the brushes are so disposed as not to crush or violently force material through the interstices of the screen whereby the impurities in the material remain on the screen, and are not forced therethrough together with the material desired. By the means provided the sifting action serves to loosen or break up the soft lumps of the flour or other material which have formed therein during storage or transportation, and also to separate the foreign matter or impurities therein, which are invariably harder than the lumps.

In baking operations it is customary to sift the flour employed immediately before passing it to the kneading machine. By sifting flour or similar material by means of a sifter constructed according to the present invention, it is completely loosened, opened up and aerated so as to be prepared for the dough-making operation.

It is obvious that the pressure with which the bristles of the brushes touch the screen is an important factor in the sifting operation with this type of machine. In order to avoid opening up or removing the cover of the machine each time the brushes are to be adjusted, either during experiments with the machine or when the brushes have been sufficiently worn as to become unsatisfactory in operation, we employ a very effective wedge mechanism by means of which the position of the brushes may be adjusted, the mechanism being preferably positioned in the hollow shaft of the sifting reel and so disposed as to permit adjustment from the exterior of the machine.

The accompanying drawings serve to illustrate the novel features, devices and combinations of the invention and the mode of operation thereof, and represent by way of example, a flour sifter which is adapted to be used in bakeries to clean, open up and aerate flour before it is passed into the kneading apparatus. While the invention is illustrated as adapted particularly for sifting flour, it is to be clearly understood that we do not desire to limit the invention to the treatment of this material alone, nor do we desire to limit the invention to the form

and construction shown in the drawings, but it will be evident to those skilled in the art that machines may be constructed or modifications may be made in such a way that they differ only in shape and in details of construction from the device herein disclosed, and may contain, nevertheless, the essential elements of the invention as defined in the claims.

Fig. 1 is a longitudinal vertical section of the sifting device through the axis thereof, in which the brushes are represented as in a worn condition, and the brush-adjusting means are indicated in the position for compensating for the worn condition thereof;

Fig. 2 is a vertical cross section of the apparatus, taken through the spider situated at the feed end of the device;

Fig. 3 is a vertical cross section taken through the spider situated at the waste outlet end of the apparatus;

Fig. 4 is a diagrammatic view of the device in which the brushes are disposed at an angle to the axis of the reel so as not to lie in the same plane;

Fig. 5 is a detail section taken on the line 5-5 of Fig. 1 showing the brushes, the brush holders and the brush-adjusting device;

Fig. 6 is a detail section taken through the hollow shaft on the line 6-6 of Fig. 1;

Fig. 7 is a section through a brush holder taken on the line 7-7 of Fig. 5;

Fig. 8 illustrates a modification of the brush holding and adjusting means in which a plurality of brushes and brush-adjusting means are employed.

In the various figures of the drawings, the same reference numerals are employed to indicate corresponding parts which serve the same or similar purposes.

Referring more particularly to the drawings, the reference numeral 9 indicates a rotary sifting reel which is covered by a screen 11 through which, with the assistance of stationary brushes 10, the material to be sifted is passed. The material which passes through the screen 11 drops into a hopper-like compartment 12 arranged at the bottom of the apparatus in the housing 13 and passes therefrom into a suitable bin or weighing hopper, or to the mixing machine, as desired, while the residue or waste which is retained in the reel passes along the screen 11 into a smaller compartment 14 at the end of the apparatus, from which it may be removed from time to time through a cover or door 15. The reel 9 is preferably so mounted as to revolve on a horizontal axis and is preferably in the shape of a truncated cone in which the material to be treated is fed thereto by suitable conveying means at the smaller end of the cone, the material being fed thereto through the interstices or spaces between the spokes of a spider wheel

16, and the waste or residue, being withdrawn from the reel or screen at the larger end of the cone between the spokes of a spider 17 positioned at the larger end of the reel.

The screen 11 for sifting material may be made of wire gauze, silk, felt or other suitable material, which may be stretched over the rims of the spider wheels 16 and 17, upon which it may be suitably held in place by means of angle irons 18 which may be attached to and extend between the spider wheels. The angle irons 18 are preferably arranged in pairs bolted back to back and fixed at their ends to the rims of the wheels 16 and 17 in order to attain a rigid construction in the reel body.

The hub of the spider wheel 16 is preferably attached to a solid shaft 20, which carries also the screw conveyor 29, by means of a screw bolt 19, the shaft 20 being rotatably mounted in bearings 21 in the front wall 22 at the conveyor end of the housing 13. The hub of the spider wheel 17, on the other hand, is preferably mounted so as to permit rotation on a stationary hollow shaft 23. The shaft 23 is rigidly secured at one end in a bearing 25 by means of a screw bolt 24, the bearing being preferably made integral with the back wall 26 at the outlet end of the device in the housing 13, and is supported or secured at its other end by means of the shaft 20. In order for the rotary shaft 20 to serve as a supporting means for the stationary shaft 23, I provide a bushing 27 between the shaft 20 and the interior wall of the shaft 23 which is held in place by means of suitable screw bolts 28, passing through suitable openings in the shaft 23.

By the rotation of the shaft 20, the spider wheel 16 fixed thereto is also rotated, causing a rotation of the reel 9 and screen 11, and the spider wheel 17, connected thereto, while the shaft 23 remains stationary, the shaft 20 rotating within the bushing 27 in the end of the shaft 23. The material which is to be fed to the machine may be conducted thereto from a suitable hopper attached, for example, to the screw conveyor 29 which is adapted to operate in a suitable housing or conveying tube 30. From the tube 30 the material passes into the reel or sifting member 9 through an opening 31 in the front wall 22 of the apparatus, the opening having preferably the same diameter as the housing 30. The bearing 21 in which the shaft 20 rotates is positioned preferably in the center of the opening 31, and is preferably rigidly suspended from the upper portion of the wall 22 by means of a single narrow bracket 32. In order to prevent any unsifted material from escaping into the compartment 12 below the reel 9, between the spider 16 and the wall 22, an annular projection 33 is provided at the inner

surface of the front wall 22 within which the outer part of the spider wheel 16 is adapted to rotate. The outer side of the rim of the spider wheel 17 is provided with 5 a suitable annular projection 34 which is adapted to turn in the recess 35 in the edge of the partition wall 37 so as to prevent residue material passing between this spider wheel and the partition wall 37 into the 10 compartment 12. In the partition wall 37 is a circular opening 36 through which the waste or residue material passes on its way from the screen to the compartment 14. The diameter of the opening is preferably substantially the same as that of the inner circumference of the annular projection 34.

The two brushes 10 illustrated in Fig. 1 are preferably fixed in position inside the reel 9 along the wire screen 11 so as to remain 20 stationary during the rotation of the screen. The brushes are arranged preferably in the same vertical plane, one below the other, although I may, in the sifting of certain materials, arrange them so as to be 25 inclined to each other and out of the plane with the axis of the screen, as shown more particularly in Fig. 4. The brushes are preferably constructed with a narrow wooden back 38 in which bristles 39 are set, the 30 brushes being so positioned that their tips will remain in contact with the screen 11. The backs 38 are preferably bolted to two bracket-like holders 40 attached to or integral with the tube or carrier 41 which is preferably rigidly fixed on the stationary shaft 23 by means of a set screw or set screws 42. With the exception of the parts of the backs 35 of the brushes which are held in the holders 40, the backs comprise two curved sides 40 which converge, forming a sharp edge at the top, as shown in Fig. 2, whereby particles dropping thereon will not settle, or stick, but will slide off and fall on the screen 11.

In cases where impurities contained in the material to be sifted are inclined to adhere to the brushes when placed in a vertical plane as shown in Fig. 1, we preferably arrange the brushes in a position inclined 50 to the axis of the shaft 23 and out of the plane therewith, as illustrated more particularly in Fig. 4, in which the lower brush is indicated by means of continuous lines, and the upper one by means of dash lines. 55 By this means the material on the screen will be assisted in its movement toward the outlet, and any material tending to stick to the brushes will be moved gradually toward the outlet.

In order to sift various kinds of material as completely, quickly and easily as possible with the type of sifter above described, the 60 form of brush best suited to sift the particular material to be handled should be selected 65 for the reason that different materials re-

quire different types of bristle, particularly as regards elasticity, length, thickness and shape thereof to attain the best results. Moreover, a particular form of brush operates best with a particular pressure on the 70 sifting screen, the amount of which depends partly on the length of the bristle and the distance of the back or supporting means for the bristles from the screen.

In the use of the machine there is more or less wear on the bristles due to rubbing against the screen, whereby the pressure of the bristles against the screen gradually diminishes until, without further adjustment, the device would eventually become substantially inoperative. It is necessary, therefore, in order to attain satisfactory operation of the device, that the relative position of the bristles to the screen should be regulated or adjusted from time to time. The 75 means generally employed to attain adjustment of the brushes in the sifting art comprises screws or levers which act directly on the brushes and which, in order to adjust, requires dismantling or partly dismantling 80 the housing to attain access thereto. This operation is tedious and requires a considerable amount of time and labor, particularly when the adjusting operations have frequently to be repeated in order to attain 85 the final adjusted position of the brushes.

In order to avoid the dismantling of the apparatus of the present invention to attain the proper set of the brushes, we preferably employ adjusting means comprising a hollow shaft adapted to contain a mechanism for controlling the position of the brushes which may be adjusted and operated by suitable means outside the machine, and in this way we entirely avoid the dismantling or 100 part dismantling of the apparatus to attain the adjustment. The means which we employ for this purpose comprises holders 40 which are preferably constructed with the use of channels 43 to which the backs 38 of 105 the brushes 10 may be rigidly attached by means of bolts 44, for example. The holders 40 are preferably held in position by means of a suitable holding device or tube 41 which is preferably provided with two outwardly 110 extending branches 46 having openings 47 therein in which rods 45 suitably attached to the channels 43, are adapted to fit and be held in position. The rods 45 are preferably 115 made integral with the channels 43, and are preferably square in cross section and rounded at the ends thereof. The holding means or tube 41 has a central opening therethrough so as to fit upon the shaft 23 upon which it may be held in position by suitable means such as a set screw 42, for example. In the walls of the hollow shaft 23, we provide openings or holes 48 which are preferably slightly larger 120 in cross section than the rods 45 and placed diametrically opposite each other in the 125

shaft so that when the tube 41 is fixed in position the openings 43 will be in alignment with the openings 47 in the branches 46 whereby the rods 45 may slide therein and 5 may be moved in a direction at right angles to the axis of the shaft. In order to hold the brushes in place, we provide, within the shaft 23, a wedge block having a main part or body portion 49 and a wedge portion 50, 10 which is tapered so as to form in section substantially an equilateral triangle, the end of the wedge lying in a straight line at right angles to the axis of the shaft 23 and in a plane passing through the axis and at right 15 angles to the direction of movement of the rods 45. The wedge 50 is preferably of metal, and of sufficient width so that the ends of the rods 45 will be maintained upon the inclined surfaces or faces of the wedge, 20 which may be suitably polished so that the rods may slide easily thereon. The size of the angle of the wedge portion 50 depends somewhat upon the size of the apparatus, but it is understood that the smaller the angle of the wedge, the smaller will be the distance which the rods 45 are moved with a given longitudinal movement of the wedge body, and consequently the finer will be the 25 adjustment of the brushes which may be attained.

The wedge 50 and the part 49 of the wedge are preferably of equal breadth and the sides of the wedge lie preferably in parallel planes so as to slide easily in suitable lateral 30 guides 51 which are preferably provided to maintain the wedge in position. In order to operatively move the wedge so as to attain adjustment of the brushes by means 35 operable externally to the sifter housing, we preferably provide a rod 52 adapted to extend outwardly through the housing 13 and which may be suitably connected to one end of the wedge member. The rod is preferably screw-threaded in a portion of its 40 length and adapted to turn in a block 54 having corresponding screw threads therein, the block being preferably cylindrical in form so as to fit into the end of the hollow shaft 23, to which it may be fastened 45 in position by means of a screw 24. The screw rod 52 is preferably connected to the part 49 of the wedge by means of a rod 55 which passes through a slot or opening in the end of the body portion 49 of the wedge 50 block and projects into a larger opening 56 therein in which it is held by any suitable means, as by a plate or washer 57, for example, which may be held in place on the rod 55 by means of a cotter pin 58. The 55 other end of the rod is provided with a suitable head or nut 59 at the end projecting externally to the housing from the shaft 23, whereby the rod may be readily turned by means of a key, for example, so as to move and adjust the position of the wedge 60

member. By these means the screw rod may be turned in any position to adjust the position of the brushes without altering the relative positions of the wedge member and the screw rod. The wedge block 49, 50 is slidably held in position between guides 51, which are preferably attached in position by connecting them at one end in the block 54, and at their other end to a disk 59 adapted to fit within the shaft 23, and fixed thereto by any suitable means, such as a set-screw 60, the distance of the block 54 from the disk 59 being such as to permit ample room for the movement of the wedge block between them. The rods 45 are preferably of such a length that when their rounded ends rest upon the front edge of the wedge 50 the tips of the bristles 39 of the brushes 10, when new (not worn), just touch the screen 11. The height of each inclined surface of the wedge 50 or the lateral distance which the brushes can be moved is preferably about equal to the average length of new bristles, or to the distance which they may be worn and still be used in this form of sifter.

In order to prevent the weight of the brushes 10, the channels 43, and the rods 45 from exerting their pressure against the screen 11, in cases where the tips of the bristles are intended only to lightly touch the latter, the free ends of the rods 45 are held on their seats on the wedge 50 by any suitable means such as springs 61, which may be fixed at one end to the tube 41 and at their other end to the channels 43 carrying the brushes 10. In order to protect the springs from dust and the material being sifted, we preferably enclose them in a thin walled telescoping housing 62 as shown in Fig. 1.

In Fig. 8 is shown a modification of the brush-holding device in which three pairs of holder rods 63, 64, and 65, each carrying a brush (not shown) are adapted to slide in the corresponding passages of the 117 branches 46 and tubes 41 of each set. Within the shaft 23 are provided a corresponding number of adjusting wedges 66, 67 and 68 which may be adjusted in position simultaneously by means of a screw rod 72 in the 115 same manner as described in connection with Figure 1. The holder rods 63 and 65 are positioned at right angles to the rods 64 and the wedges 66, 67, and 68 and the corresponding guides 69, 70 and 71 between which they slide are suitably arranged in accordance therewith, as shown in Fig. 8 of the drawing. The tip of the wedge 66 is connected to the back or body part of the wedge 67 which is turned at right angles to the wedge 66, the wedges being connected by means of the rod 72. In a similar manner the tip of the wedge 67 is connected to the back of the wedge 68 by means of the rod 73, the wedge 68 lying in a position parallel 125 129

to that of the wedge 66 and at right angles to the wedge 67. The wedges and the connecting rods are preferably made integral, although the parts may be separately connected if desired. The guides 69 are preferably attached at one end to the block 54 fixed to the shaft 23 by means of a screw bolt 24, and at the other end thereof to a disk 74, fixed to the shaft 23 by means of a screw 75, and provided at its center with an opening 76 in which the rod 72 is adapted to slide. The guides 70 are preferably fixed at one end to the disk 74 and at the other end to a disk 77, which may be fastened to the shaft 23 by means of a screw 78 and in which is an opening 79 through which the rod 73 is adapted to pass or to move during the adjustment of the holding device. The guides 71 are fixed at one end to the disk 77 and at the other end to a disk 80, fixed to the shaft 23 by means of a screw 81. The distance of the bar 54 from the disk 74 and the distances of the disks 74, 77 and 80 from each other are so adjusted as to give ample room for the movement of the wedges 66, 67 and 68 respectively. It is to be understood that any suitable number of brushes, brush holders and adjusting wedges may be employed which may be arranged in a manner similar to that shown and described in connection with Fig. 8.

We claim:

1. In a machine of the kind described, a sifting reel in the form of a truncated cone with open ends, means for feeding material to be sifted to the smaller end of said cone, means for removing the waste residue from the said cone at the larger end thereof, means for rotating the said reel on a horizontal axis, a stationary brush supported within the said reel and extending substantially the length of the inner surface of the said reel on one side of said axis, a second stationary brush extending substantially the length of the inner surface of the said reel on the other side of said axis, and means for maintaining said brushes in proximity to the inner surface of said reel during the rotation thereof.

2. In a machine of the kind described, in combination a rotatable sifting reel having the shape of a truncated cone, the material to be sifted entering at its smaller end and the waste residue leaving at its wider end, stationary brushes provided inside the said reel for its surface to be swept while passing across the same, and a screw conveyor for passing the material to be sifted into the said reel, the shaft of the said conveyor being extended inside and coaxially to the said reel and serving to rotate the same.

3. In a machine of the kind described, in combination a sifting reel having the shape of a truncated cone, a smaller spider wheel supporting the smaller end of the said reel,

the material to be sifted entering between its spokes, a larger spider wheel supporting the wider end of the said reel, the waste residue leaving between its spokes, a driving shaft to which the said smaller spider wheel is rigidly fixed, a stationary hollow shaft partly surrounding the said driving shaft and revolubly carrying the said larger spider wheel, brushes arranged along the inner surface of the said reel, and adjustable holders fixing the said brushes to the said stationary shaft.

4. In a machine of the kind described, in combination a sifting reel, stationary brushes arranged therein to sweep its inner surface, holders supporting the said brushes, a hollow shaft arranged coaxially to the said reel, the said shaft having openings in the wall thereof at points corresponding to the position of said holders, an adjusting device contained in the said hollow shaft and adapted to act through the said openings on the said holders, and means for operating the said adjusting device from the end of the said hollow shaft outside the machine.

5. In a machine of the kind described, in combination a sifting reel, brushes arranged therein to sweep along its inner surface, holders supporting the said brushes, a hollow shaft arranged coaxially to the said reel, the said shaft having openings in the wall thereof at points corresponding to the position of the said holders, wedges disposed within the said hollow shaft and adapted to act through the said openings on the said holders and thus to adjust the said brushes, and means for operating the said wedges from the end of the said hollow shaft outside the machine.

6. In a machine of the kind described, in combination a sifting reel and two brushes within said reel arranged opposite to each other and adapted to sweep along the inner surface of said reel, two supports, each of which is fixed to one of said brushes, two angular rods forming part of the said supports and arranged at right angles to the axis of said reel, a hollow shaft positioned coaxially to the said reel, the said shaft having two openings in the wall thereof and opposite to each other, corresponding in position with that of said angular rods, two hollow guides for the said rods in registration with the said openings, an equilateral wedge within said hollow shaft, means for moving said wedge to and fro within said hollow shaft so that the inclined faces of the wedge may pass underneath the said openings in the direction of the axis of the said shaft, and means for operating the said wedge from the end of said shaft outside of the machine, the length of the said rods being such that their free ends rest on the front edge of the said wedge when the tips of the bristles of the said brushes, when new, just

touch the inner surface of the said reel, and the total inclination of the slanting surfaces of the said wedge and the distances of the tops of the said hollow guides from the point of the said rods at which they are joined to the said supports, being such that the total extent of the possible adjustment of the said brushes is practically equal to the length of the bristles thereof.

10 7. In a machine of the kind described, in combination a sifting reel, brushes arranged therein so as to sweep along its surface, supports fixed to the said brushes, angular rods forming part of the said supports and arranged at right angles to the axis of the said reel, a hollow shaft arranged coaxially to the said reel, wedges slidably arranged in the said shaft, openings provided in the latter corresponding to the position and cross section of the said rods, hollow guides fixed round the said openings for the said rods to slide in, the length of the latter being such, that, passing through the said hollow guides and the said openings into the said hollow shaft onto the inclined surfaces of the said wedges, they rest on the front edges of the latter, when the tips of the bristles of the said brushes, being new, just touch the said reel, resilient means for holding the lower ends of the said rods against the inclined surfaces of the said wedges, and means for moving the wedges so as to adjust the said brushes from the end of the said hollow shaft outside the machine.

15 8. In a machine of the kind described, in combination a sifting reel, brushes arranged therein to sweep along its inner surface, holders supporting the said brushes, a hollow shaft arranged coaxially to the said reel, the said shaft having openings provided in the wall thereof at points corresponding to the position of the said holders, wedges disposed within said hollow shaft and adapted to operate the said holders to adjust the said brushes, a spring fixed at one end to the said hollow shaft and at the other end to the said brushes, the telescoping housing enclosing the said spring for protection against dust, and means for operating the said wedges against the pressure of the said spring.

sure of the said spring from the end of the said hollow shaft outside the machine.

9. In a machine of the kind described, in combination a sifting reel having the shape of a truncated cone, a smaller spider wheel adapted to support the end of the said reel at which material to be sifted is fed, a larger spider wheel adapted to support the larger end of the said reel at which waste residue is discharged, a housing surrounding the said machine, a driving shaft rotatably supported in bearings provided in a wall of the said housing, means for connecting said smaller spider wheel to said driving shaft, a hollow stationary shaft in axial alignment with said driving shaft, said stationary shaft having a bore of slightly larger diameter than said driving shaft and extending over the end of said driving shaft within said reel, means for mounting the said larger spider wheel on the said stationary shaft, bushings provided in an end of said hollow shaft within said reel for said driving shaft, a support for said hollow shaft arranged at the opposite wall of the said housing and carrying the end of said hollow shaft outside of the said reel, two brushes arranged opposite to each other along the inner surface of said reel, two supports, one for each of the said brushes, two rods, each of which forms part of the said supports, the said rods being arranged substantially at right angles to said hollow shaft, two openings provided in the said hollow shaft opposite to each other and corresponding in position to that of said rods, two hollow guides for said rods registering with said openings, an equilateral wedge slidably arranged within said hollow shaft and adapted to support the said rods at the free ends thereof, the length of the rods being such that the free ends thereof may rest on the forward edge of said wedge when the tips of the bristles of said brushes while new, just contact with the inner surface of the said reel, and means for operating said wedge from the end of the said hollow shaft outside the machine.

EUGENE GASE.
LOUIS CHARLES REESE.
